Samuel Marson, New York, N.Y.

Application April 22, 1957, Serial No. 45,815

Term of patent 3½ years

(Cl. D61—1)

Fig. 2.

Fig. 1.

Fig. 4.

Fig. 3.

Fig. 1 is a front elevational view of an accessory bracket for a camera or similar article, showing my new design;

Fig. 2 is a top plan view;

Fig. 3 is a side elevational view, the opposite side being substantially a mirror image thereof; and

Fig. 4 is a rear elevational view thereof.

The broken line showing of a camera in Fig. 3 is for illustrative purposes only.

I claim:

The ornamental design for an accessory bracket for a camera or similar article, substantially as shown and described.
